UNITED STATES PATENT OFFICE.

JOSEPH OTTNER, OF NEW BRITAIN, ASSIGNOR TO HART MANUFACTURING COMPANY, OF KENSINGTON, CONNECTICUT.

DESIGN FOR DRAWER-PULL.

Specification forming part of Design No. 5,702, dated March 19, 1872.

To all whom it may concern:

Be it known that I, JOSEPH OTTNER, of New Britain, in the county of Hartford and State of Connecticut, have invented and produced a new and original Design for a Drawer-Pull, of which the following is a specification:

The nature of my design is fully represented in the accompanying drawing.

A represents the body of the pull of the general form, as shown. The sides and upper edges of this are ornamented by raised work, consisting, first, of a broad border with

curved depressions; and second, of angular or T-shaped ledges, as shown. The face B of the pull is surrounded by a raised edge, inside of which is raised ornamental work, as shown. At each end is the wing for the screw-holes a.

I claim as my invention—

The design for a drawer-pull, as shown.
JOSEPH OTTNER.
